A. RICKENBACHER

DOORSTOP

Filed Sept. 8, 1925

UNITED STATES PATENT OFFICE.

ADOLPH RICKENBACHER, OF LOS ANGELES, CALIFORNIA.

DOORSTOP.

Application filed September 8, 1925. Serial No. 54,932.

This invention relates to a door stop and it is an object of the invention to provide a device for stopping or holding a door, or the like, in any desired position.

5 It is an object of this invention to provide a door stop adjustable to offer any degree of resistance to movement of a door ranging between only slight resistance and practically positive resistance.

10 It is another object of this invention to provide a door stop which is easily and quickly adjustable to vary the resistance offered to movement of the door.

15 A further object of this invention is to provide a door stop of simple, inexpensive construction and which is simple to install and operate.

20 The various objects and features of my invention will be best and more fully understood from the following detailed description of a typical preferred form of the invention throughout which description reference is had to the accompanying drawings in which:

25 Fig. 1 is a view showing the device provided by this invention applied to a typical door.

Fig. 2 is a vertical detailed sectional view of the construction provided by this invention.

30 Fig. 3 is a side elevation of a portion of the device being a view taken as indicated by line 3-3 on Fig. 2.

Fig. 4 is a detailed sectional view taken 35 as indicated by line 4-4 on Fig. 2.

Fig. 5 is a plan section taken as indicated by line 5-5 on Fig. 2.

40 Fig. 6 is a side elevation of a floor plate suitable for use in connection with the other parts of the device.

45 My present invention is capable of embodiment in various forms and is useful in various situations. The device of the present invention is particularly suited for use in connection with a door and is operable to offer resistance to movement of the door so that it will remain in place unless deliberately operated. I will proceed to describe a typical preferred form of the invention 50 as applied to a door such as will be found in an ordinary dwelling.

In the drawings numeral 10 designates a typical door mounted in the usual casing 11 on hinges 12. The device provided by this 55 invention is adapted to be mounted on the

door 10 to engage the floor 13 over which the door swings to offer resistance to movement of the door.

The device provided by this invention includes, generally, a cylindrical body 14 adapted to be mounted on the door 10, a stem 15 carried by the body, a roller 17 carried by the stem to engage in the floor 13, a spring 18 carried by the body and normally urging the stem downwardly, control means 19 operable to control the rotative position of the stem with reference to the body, and various other parts, the details and functions of which will be hereinafter described.

70 The body 10 is cylindrical in form and is closed at its upper end by a cap 20. Brackets 21 are provided at the exterior of the body whereby it can be mounted on a door 10, or the like, by suitable means such as 75 screws.

75 The stem 15 extends upwardly through the body and projects through an opening 23 in the cap 20. The opening 23 in the cap is preferably round and carries the stem so that it can rotate and move longitudinally. In the form of the invention shown in the drawings the stem is formed of two flat metal strips arranged together. The stem 15 is supported or guided in the lower portion of the body by a disc 24. The disc is supported on an upwardly facing shoulder 25 on the stem and is provided at the periphery with a flange 26 slidably fitting the body. The downward movement 80 of the stem in the body may be limited by suitable stop means, for instance the upper ends of strips of metal out of which the stem is formed may be bent or turned outwardly above cap 20 as shown at 27.

85 The roller 17 which is adapted to engage the floor is mounted on the lower end of the stem, for instance, in a yoke 30 formed at the lower end of the stem. The roller may be carried on a pivot pin 31 mounted in the yoke and is preferably provided with a friction tread 32. In practice I prefer to form the roller of rubber, as this material is easily obtained and formed, and will not scratch or mar the floor on which it operates.

90 The spring 18 provided for normally urging the stem downwardly may be a helical spring arranged under compression between the cap of the body and the disc 24. With 95 this arrangement the spring normally urges 100

the stem downwardly; the downward movement of the stem being limited by the outwardly turned part 27 at the upper end of the stem.

5 The means 19 provided for controlling the rotative position of the stem with reference to the body may include a part in the form of a plate 35 connected with or carried by the stem and an operating lever 36 projecting from the plate 35 through an opening 37 in the side of the cap so that it can be engaged at the exterior of the body. In the preferred arrangement the plate is arranged between the upper end of the spring 18 and 10 the cap 20 and is provided with an opening which slidably passes the stem but prevents relative rotary movement between the plate and stem. The operating lever 36 may be in the form of a projection extending from 15 the periphery of the plate. The lever 36 operates to hold the plate against rotation with reference to the body by engaging notches 40 provided in the upper edge of the opening 37 in the cap. The lever 36 co-operates with 20 the notches 40 so that the lever and plate 35 will not turn or rotate with reference to the body, unless deliberately operated by engagement with the outer part of the levers. The plate 35 being thus held against rotation operates to hold the stem against rotation. 25

As means for rendering the device inoperative, for instance, for setting the device in position where the roller is in a raised position out of engagement with the floor, I may 30 provide a washer 42 between the top of the cap 20 and the outwardly parts 27 of the stem. The washer 42 may be provided with an opening which slidably passes the stem. The stem may be provided with notches 50 at a point spaced from its upper end and into which the washer 42 may be turned. Under normal conditions the washer does not in any way interfere with the operation 40 of the device. However, when desired the washer may be operated to hold the device inoperative upon being turned to engage the notches 50 after the stem has been moved upwardly to move the notches into line with the washer. 45

50 The floor plate 51 provided by this invention is adapted to be applied to the floor to cooperate with the device herein above described. The plate may be formed of sheet metal and may be provided with a 55 hump part 52 over which the roller may be passed. Further, the plate may be provided with a stop part 53 past which the roller cannot be moved and which therefor forms a positive stop limiting movement of the door. The plate may be provided between 60 the hump 52 and stop part 53 with a concave socket part 54 adapted to receive and hold the roller.

65 In operation the device is applied to a door 10 in the manner shown in Fig. 1 of

the drawings, it being preferred to mount it at the outer part of the door as shown in the drawings. The floor plate is mounted on the floor by suitable means such as screws or tacks, to be in the path of movement of the roller, for instance, at a point to hold the door in a wide open position. The device is mounted on the door so that the spring normally holds the roller in pressure engagement with the floor and the spring is 70 made strong enough to hold the roller fairly tight against the floor. When the stem is adjusted with reference to the body so that the roller faces its line of movement the door is yieldingly held against movement about 75 the hinges because of the contacting of the roller with the floor due to the action of the spring. If it is desired to increase the resistance to the movement of the door the lever 36 may be turned or moved in the opening in the side of the cap turning the stem and therefore the roller so that the roller does not face squarely the path of its movement. With the roller thus faced at 80 an angle to the direction in which it is moved it will have more or less of a dragging action. The resistance to movement of the door may be thus varied by varying the angularity of the roller, that is the direction in which the roller faces with reference 85 to its path of movement. If the roller is turned at right angles to the path of movement it will have a positive dragging action and no turning action. In this case the device operates practically as a positive stop 90 for holding the door against movement. This is particularly true when the roller is formed of rubber sufficiently soft to effectively grip the floor. Upon operating the door so that the roller passes over the hump 95 of the floor plate it is securely and effectively held against movement, even though the roller may be adjusted to offer only the minimum resistance to movement.

Having described only a typical preferred form of my invention I do not wish to limit myself to the specific details set forth, but wish to reserve to myself any changes or variations that may appear to those skilled in the art or fall within the scope of the 105 following claims:

Having described my invention, I claim:

1. A door stop including a body to be mounted on the door, a stem carried by the body, a roller mounted on the lower end of the stem to engage the floor over which the door swings, means normally urging the stem downwardly, and means for holding the stem in various rotative positions with reference to the body. 120

2. A door stop including, a body to be mounted on the door, a stem carried by the body, a roller carried by the lower end of the stem to engage the floor over which the door swings, a spring carried in the body 125 130

normally urging the stem downwardly and means for holding the stem in various rotative positions with reference to the body.

3. A door stop including, a cylindrical body closed at its upper end, a stem carried by the body, a part on the stem guiding it in the lower part of the body, a roller on the lower end of the stem, a spring in the body under compression between the upper end of the body and said part, and means for holding the stem in various rotative positions with reference to the body.

4. A door stop including, a body to be mounted on a door, a stem carried by the body, a roller carried by the lower end of the stem to engage the floor over which the door swings, means for releasably holding the stem against rotation relative to the body, means normally urging the stem downwardly, and releasable means for setting the stem in position when the roller does not engage the floor.

5. A door stop including, a body to be mounted in the door, a stem carried by the body, a roller carried by the stem to engage the floor over which the door swings, and means for holding the stem in various rotative positions with reference to the body, said means including a part on the stem within the body and an operating lever extending to the exterior of the body through an opening in the body.

6. A door stop including, a body to be mounted on the door, a stem carried by the body, a roller carried by the stem to engage the floor over which the door swings, and means for holding the stem in various rotative positions with reference to the body, said means including a part on the stem within the body, an operating lever extending from said part through an opening in

the body, and parts on the body at the opening for holding the lever against movement.

7. A door stop including, a body to be mounted on the door, a stem carried by the body, a roller mounted on the lower end of the stem to engage the floor over which the door swings, means normally urging the stem downwardly, means for holding the stem in various rotative positions with reference to the body, and a floor plate to be engaged by this roller.

8. A door stop including, a body to be mounted on the door, a stem carried by the body, a roller mounted on the lower end of the stem to engage the floor over which the door swings, means normally urging the stem downwardly, means for holding the stem in various rotative positions with reference to the body, and a floor plate to be engaged by the roller and including a part over which the roller can pass and a part to positively stop the roller.

9. A door stop including, a body to be mounted on the door, a stem carried by the body, a roller carried by the lower end of the stem to engage the floor over which the door swings, a spring carried in the body normally urging the stem downwardly, and means for holding the stem in various rotative positions with reference to the body, said means including a part on the stem in the body, a lever extending from said part through an opening in the body, and notches at one edge of the opening in the body to be engaged by the lever, said part being engaged by the spring so that the lever is normally held in engagement with the notches.

In witness that I claim the foregoing I have hereunto subscribed my name this 2nd day of Sept., 1925.

ADOLPH RICKENBACHER.
